UNITED STATES PATENT OFFICE.

THOMAS J. STEARNS, OF BOSTON, MASSACHUSETTS, ASSIGNOR TO ROXBURY CARPET COMPANY, OF SAME PLACE.

DESIGN FOR CARPET.

Specification forming part of Design No. **11,366**, dated August 26, 1879; application filed July 14, 1879.
[Term of patent 34 years.]

To all whom it may concern:

Be it known that I, THOMAS J. STEARNS, of Boston, in the county of Suffolk and State of Massachusetts, have invented a new and original Design for Carpets, of which the following is a specification.

My design is fully shown in the accompanying photographic illustration forming a part of this specification.

In said illustration, A represents a figure extending longitudinally of the pattern, having a lace-insertion border and conventional floral center. The figure A rests upon a figure, B, which I denominate a Grecian square, the same being partly covered by the figure A.

D represents a transverse figure, somewhat similar in form and ornamentation to the figure A, and alternating with the latter through the center of the pattern. The figure D rests upon two diagonal bands or figures, E E, resembling lace-work, and the figures E are ornamented with flowers, edgings, and knotted ribbons, holding sprays or bouquets of flowers, 4 4 4 4.

F G represent curved figures, acting as bass-relief for two of the bouquets 4. Said figures F G and the small diagonal figures H I are adjuncts to the main figures A D.

The whole rests on a ground of small interlaced Grecian work, (represented by J J J J.)

I claim—

1. The design for a carpet, having the Grecian square B and the longitudinal figure A resting thereon, substantially as shown.

2. The design for a carpet, having the transverse figure D, and the diagonal bands or figures E E, in which the figure D rests, substantially as shown.

3. The design for a carpet, having the transverse figure D, the diagonal bands or figures E E, and the bouquets 4 4 4 4, arranged around the figure D, substantially as shown.

4. The design for a carpet, having the figures A B D E, and their adjuncts F G H I, and bouquets 4 4 4 4, and the groundwork J J J J, substantially as shown.

In testimony whereof I have signed my name to this specification, in the presence of two subscribing witnesses, this 11th day of July, 1879.

THOMAS J. STEARNS.
